UNITED STATES PATENT OFFICE

FRED BUTZBACH, OF CLINTON, IOWA

WINDOW CONSTRUCTION

Application filed April 15, 1928. Serial No. 355,248.

The object of my invention is to provide a window construction of simple, durable, and comparatively inexpensive manufacture.

More particularly, it is my object to provide a window construction in which the head casing has its lower edge provided with a longitudinal groove throughout the length thereof and the side casings have upwardly extending tongues to fit in said groove of the head casing for properly and efficiently aligning the side casings with the head casing.

Still a further object is to provide the groove between the side casings to prevent the water which runs down the head casing from following the lower edge thereof and finding its way across the lower surface of the head jamb and then running down on to the window.

Still a further object is to provide said groove extending between the side casings so that an auxiliary frame such as the frame of a storm sash or window screen may be provided with an upwardly extending tongue to fit into the groove, whereby to facilitate easy installation of the auxiliary frame relative to the window frames.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is an outside elevation of a window construction embodying my invention and showing a storm sash in position.

Figure 2 is a vertical sectional view of the same.

Figure 3 is an enlarged sectional view on the line 3—3 of Figure 1.

Figure 4 is an enlarged sectional view on the line 4—4 of Figure 1, illustrating a window screen instead of a storm sash.

Figure 5 is a perspective view of a head casing provided with the groove referred to in my specification; and

Figure 6 is a perspective view of an upper

rail of a storm sash showing the tongue formed thereon.

On the accompanying drawings, I have used the reference character A to indicate generally, a window frame. The window frame A includes a sill 10, head casing 12, and side casings 14. The head casing 12 is provided throughout its length with a groove 16. The groove 16 is in the lower edge of the head casing.

The upper end of each side casing 14 is provided with an upwardly extending tongue 18 adapted to tightly fit in the groove 16, whereby the side casings 14 are conveniently and properly aligned relative to the head casing 12 when the carpenter is assembling the window frame A just before building it into the frame of the building.

In Figures 1 and 5, the brackets a indicate the portions of the groove 16 into which the tongues 18 extend. The bracket b indicates the intermediate portion of the groove adapted to coact with an auxiliary frame such as a storm sash or window screen frame, as I will now describe.

In Figures 1, 2 and 6, I have illustrated a storm sash B including an upper rail member 20. The rail member 20 is provided throughout its length with an upwardly extending tongue 22. The tongue 22 is adapted to position the frame of the storm sash B relative to the head casing 12, whereby to facilitate installation of the storm sash and to insure the proper alignment of the upper end thereof relative to window frame A. This makes the job of installing the storm sash B much simpler and safer, as the tongue 22 on the upper end of the sash may be caused to enter the portion b of the groove 16 and then the lower end of the sash swung inwardly, as indicated by the arrows 24 and 26 in Figure 2.

Thus, while pushing the lower end inwardly, the upper end will not fall outwardly, which would make the storm sash obviously hard to handle. Less hardware can be used with this type of construction. For instance, in Figures 1 and 2, I have shown pivoted buttons 28, two of which are provided adjacent the lower end of the

storm sash. Where the groove 16 and tongue 22 are not provided, additional buttons 28 must be provided for the upper end of the storm sash. If desired, the ordinary hinge type of hardware along the upper rail of the sash may also be provided for hanging the sash on and the tongue and groove connection between the storm sash and the head casing will facilitate installation of the storm sash even when such hardware is provided.

Another desirable advantage of my construction is that a better wind-tight joint is provided between the upper end of the storm sash B and the head casing 12.

15 Referring to Figure 4, a window screen C has been illustrated. The upper rail 30 of the screen C is shown formed with a groove 32 into which a spline 34 has been glued. The spline 34 acts as a tongue to contact with the portion b of the groove 16 in the head casing 12. In constructing the storm sash frame or the window screen frame either a tongue may be formed on the upper rail or a spline may be provided, as shown in Figure 4. Each construction results in the tongue desired for the purpose of entering the groove 16.

It will be noted that the inner edge of the spline 34 is slightly beveled, as indicated at 36 and the tongue 22 is similarly beveled so that the auxiliary frame may be swung outwardly, as indicated by the arrow 38 before being pulled downwardly, as indicated by the arrow 40 without breaking the tongue or spline off. This is necessary also in installing the auxiliary frame.

From the foregoing description, it will readily be seen that I have provided a window construction in which the tongue and groove arrangement facilitates both the assembly of the window frame and the installation of storm sash or window screens.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In a window construction, a head casing having its lower edge provided with a central longitudinal groove throughout its length.

2. In a window construction, a head casing having its lower edge provided with a longitudinal groove throughout its length and side jambs each having a tongue at its upper end to fit into said groove.

3. In a window construction, a head casing having its lower edge provided with a longitudinal groove throughout its length, side jambs each having a tongue at its upper

end to fit into said groove, and an auxiliary frame between said side jambs and having a projecting tongue along its upper edge to fit in said groove, said tongue and groove preventing both inward and outward movement of the top of the auxiliary frame with respect to said head jamb.

4. In a window construction, a pair of side jambs and a head casing having its lower edge provided with a longitudinal groove between said side jambs and an auxiliary frame between said side jambs and having a projecting tongue along its upper edge to fit in said groove, said tongue and groove preventing both inward and outward movement of the top of the auxiliary frame with respect to said head jamb.

5. In a window construction, a head casing having its lower edge provided with a longitudinal groove and an auxiliary frame having a projecting tongue along its upper edge to fit in said groove, said tongue and groove preventing both inward and outward movement of the top of the auxiliary frame with respect to said head jamb.

6. In a window construction, a head casing having its lower edge provided with a longitudinal groove, and an auxiliary frame between said side jambs and having a projecting tongue along its upper edge to fit in said groove, the inner edge of said tongue being beveled to facilitate entry of the tongue into the groove.

7. In a window construction, a head casing and an auxiliary frame having a tongue and groove connection with each other for positioning the auxiliary frame with respect to the head casing and thereafter preventing both inward and outward movement of the top rail of the auxiliary frame with respect to the head casing.

8. In a window construction, a head casing and an auxiliary frame having a tongue and groove connection with each other for positioning the auxiliary frame with respect to the head casing and thereafter preventing both inward and outward movement of the top rail of the auxiliary frame with respect to the head casing, said tongue having one edge thereof beveled to facilitate entry of the tongue into the groove.

FRED BUTZBACH.
